UNITED STATES PATENT OFFICE.

EDGAR E. WARNER, OF MILWAUKEE, WISCONSIN.

PASSENGER-GUARD AND TICKET-COLLECTING GATE.

SPECIFICATION forming part of Letters Patent No. 413,883, dated December 30, 1890.

Application filed January 29, 1889. Serial No. 297,949. (No model.)

To all whom it may concern:

Be it known that I, EDGAR E. WARNER, of Milwaukee, in the county of Milwaukee, and in the State of Wisconsin, have invented certain new and useful Improvements in a Combined Passenger-Guard and Ticket-Collecting Gate; and I do hereby declare that the following is a full, clear, and exact description thereof.

My invention relates to the platforms of railway-coaches; and it consists in an attachment thereto comprising a combined passenger-guard and ticket-collecting gate, as will be fully set forth hereinafter, and subsequently claimed.

In the drawings, Figure 1 is a side elevation of one end of a railway passenger-coach and platform with my improved device attached thereto. Fig. 2 is a horizontal section on the line 2 2 of Fig. 1, and Fig. 3 is a vertical section on the line 3 3 of Fig. 2.

A represents one end of an ordinary railway-coach, B a portion of the platform, and C the steps depending therefrom.

D is a vertical rod or rail secured to the end of the coach, and E E represent a portion of the guard or brake-supporting rail, all of the foregoing being common to railway-coaches and of any ordinary construction.

My attachment (which is so constructed as to be applied to any ordinary railway-coach now in use) consists, primarily, of the passenger guard or gate and the ticket-collecting box G attached thereto, with mechanism for the reciprocal automatic operation of the said guard and box. The vertical rail D is provided with an upper collar a and a lower collar b, whereby the gate or guard F is hung, as shown in Figs. 1 and 3, from rings or eyes c c, attached to or formed on said gate, which in its simplest preferred form consists of upper and lower horizontal rods d e, united by vertical rods f f', the lower inner corner of said gate being left open, as shown at g, to receive the box G when the gate is closed, above which space I show a short horizontal rod e' and shorter vertical rods, and while I have thus particularly described a simple form of gate it will be understood that the particular construction of the gate is immaterial and may be varied as desired. The rail D carries an intermediate collar h, on which rests a segmental toothed block H, per-

forated for the passage therethrough of the rail D and the inner vertical end rod f' of the gate F, which latter is rigidly secured to said block H, as by pin, screw, or bolt i. From the box G there extend two curved arms, the upper one j terminating in a segmental toothed end J, meshing with the segmental toothed block H, just named, and the lower arm k, having a vertical perforation in its free end for the reception of the pintle m of an arm K, which screws into or is otherwise attached to the vertical rail D, the segmental end J of the upper arm j being similarly perforated for the reception of the vertical part of the angle-arm I, which is similarly attached to the rail D, and carries a collar or nut n on its lower end to support the arm j and keep it in place on said arm I. The ticket-collecting box G is thus hinged to the same rail as is the gate F, and forms an integral and reciprocally-moving part of the latter, as hereinafter explained. The said box G is provided with a slot or hopper o in the top and a stop q projecting from its free end for engagement with one of the bars of the gate, and preferably with a window p on one side, as well as with any suitable locked slide or door r or other device for giving access to its contents.

The gate F is preferably provided with a lock or latch s, engaging with a keeper t on the guard-rails E, and any form of lock may be employed.

My device is intended especially for use in connection with a double ticket, or one having a detachable coupon or an accompanying ticket-check, and its operation will be readily understood from the foregoing description of its construction. The platforms of all the coaches are provided with the guards or gates, and on such platforms as are to be used for the entrance of passengers to the train bramen or other train-men are stationed, and when a passenger appears the train-man examines the ticket and detaches the coupon-check (or retains the duplicate in whatever form it may be) and swings the gate inward, as shown in dotted lines in Fig. 2, which action by reason of the toothed segments H J serves to automatically swing the box G outward out of the way of the steps and against the end of the coach, as also shown in dotted

lines in said Fig. 2, and then this coupon or check is dropped into the box G and the passenger enters the coach, and then the train-man swings the gate back to place, thus automatically drawing the box G back to the closed position by reason of the described action of the toothed segments II J, and similarly to close the device. The train-man may, if more convenient, pull on the box G and turn it to place over the steps, and this will close the gate, the action being perfectly reciprocal, sure, and automatic.

My device will be found especially useful for guarding against passengers entering the train without tickets at such stations as do not employ a regular gate, and thereby do away with cash fares; and, further, the box G serves as a complete check upon the tickets taken up in the train and enables the company to dispense with ticket-collectors now employed in addition to the conductors on several roads, and as all the gates save those in charge of the brakemen or train-men can be locked there is no need of employing any extra assistants to take charge of the ticket-collecting gates.

Having thus fully described my invention, what I claim as new, and desire to secure by Letters Patent, is—

30 1. An improved attachment to railway-coaches, consisting of a guard-gate arranged to be hinged upon the vertical rail of the end

of the coach, a ticket-receptacle partially inclosed by said gate and arranged to be hinged also upon said rail, and means, substantially 35 as described, for moving the gate and box simultaneously, for the purpose described.

2. In combination with the platform of a railway-coach and its vertical rails, a passenger-guard gate hinged to one of said rails, 40 a ticket-collecting box hinged to the same rail and connected to said gate, and means whereby a movement of either the gate or box in one direction will move the other part in the opposite direction, substantially as set 45 forth.

3. In combination with the platform of a railway-coach and its vertical rails, a passenger-guard gate hinged to one of said rails, 50 a ticket-collecting box hinged to the same rail, a toothed segmental block loose on said rail and secured to said gate, and an arm secured to said box and having a toothed segmental end in engagement with the said toothed segmental block, substantially as set 55 forth.

In testimony that I claim the foregoing I have hereunto set my hand at Milwaukee, in the county of Milwaukee and State of Wisconsin, in the presence of two witnesses.

EDGAR E. WARNER.
